TRACK SANDER

Application filed October 14, 1927. Serial No. 226,242.

This invention relates to track sanders for locomotives and the like, and especially to sanders of the pneumatic type in which air under pressure is employed to draw the sand from a sand box or other supply chamber or reservoir and cause it to flow into a discharge pipe leading to the desired point of application.

The invention has for an object to provide a sander in which waste of sand or discharge thereof at improper times is avoided but which at the proper times will deliver the sand in a fine and even stream as required. Another object of the invention is to provide a pneumatic sander in which accidental clogging of the sand passage by stones or lumps and of the air passages and ports by scale and sediment is reduced to a minimum but in which any obstruction which may occur can be readily removed with minimum trouble and without dismantling or disconnecting the apparatus. A further object of the invention is to provide a pneumatic sander in which erosion of the interior walls of the sand chambers and passages by the combined action of the sand and air jets is avoided. A still further object of the invention is to provide a sander installation in which sand from a single supply chamber or reservoir can be applied to the rail or equivalent traction surface at a plurality of points.

The foregoing and other objects of the invention, together with means whereby the latter may be carried into effect, will best be understood from the following description of certain forms or embodiments thereof illustrated in the accompanying drawings. It will be understood, however, that the particular constructions described and shown have been chosen for purposes of exemplification merely, and that the invention, as defined by the claims hereunto appended, may be otherwise embodied without departure from the spirit and scope thereof.

In said drawings:

Fig. 1 is a diagrammatic representation of a portion of a locomotive having applied thereto a track sander installation embodying the invention.

Fig. 2 is an enlarged longitudinal section of the sander shown in Fig. 1.

Fig. 3 is a section taken substantially on the line 3—3, Fig. 2.

Fig. 4 is a view similar to Fig. 2 showing a modified arrangement.

Fig. 5 is a view similar to Fig. 1 showing an installation for delivering sand to the track at points respectively in front of and behind the front and rear driving wheels of a locomotive.

Fig. 6 is an enlarged elevation, partly in longitudinal section, of the sander shown in Fig. 5.

Fig. 7 is a section taken substantially on the line 7—7, Fig. 6.

Fig. 8 is a section taken substantially on the line 8—8, Fig. 7.

In Fig. 1 is shown a portion of a locomotive having a boiler 15, sand dome 16, driving wheels 17, and to which is applied a track sander indicated as a whole by the letter A. As shown in Fig. 2, the sander A includes a fitting 18 providing a sand supply chamber or reservoir with which communicates a sand supply pipe 19 leading from a sand box (not shown) located in the sand dome 16 (Fig. 1). Connected with the fitting 18, as by bolts 14 (Fig. 3), is the sand drafter which comprises a fitting 20 having a substantially straight, horizontal, unobstructed sand passage 21 leading laterally from the sand supply chamber of the fitting 18 adjacent the bottom of the latter. At the mouth or inlet end of the passage 21 the upper wall of the fitting 20 is projected slightly into the sand supply chamber or reservoir to form a dam or baffle 22. Adjacent its outer end the sand passage 21 communicates with a downwardly disposed outlet opening 23 to which is con-

5 nected a sand delivery pipe 24 leading to the rail, the cross-sectional area of the passage 21 being relatively small with respect to that of the outlet 23. At its extreme outer end 10 beyond the outlet 23 the sand passage 21 is provided with a clean-out opening 25 which is normally closed by a removable plug 26. Above the sand passage 21 the fitting 20 is formed with an air passage 27 which is disposed at a generally downward inclination to 15 the horizontal from its inlet 28 at one end to a clean-out opening 29 at the other, said inlet being supplied with air under pressure from any suitable source under the control of the usual engineer's valve (not shown) 20 through a pipe 30, and said clean-out opening being normally closed by a removable plug 31. The air passage 27 is connected with the sand passage 21 by air ports or orifices arranged to discharge air under pressure 25 into the latter passage in such a manner as to cause the sand to flow therethrough from the supply chamber to the outlet 23. One of these air ports or orifices is formed in a nozzle 32 arranged to direct a jet of air into the outlet 23, while the other comprises a 30 passage 33 in the fitting 20, said passage having a restricted inlet formed in a bushing 34 and terminating in a nozzle 35 arranged to 35 discharge its jet imminately above the inlet of the sand passage into the sand supply chamber in a direction substantially parallel to the axis of the former and the bottom of the latter. The nozzle 32 and bushing 34 are formed with heads 36 at the inlet ends of the air ports therethrough, whereby the inlets of said ports are elevated above the adjacent bottom wall of the air passage 27. Said inlets are located adjacent to one another and to a 40 clean-out opening 37 normally closed by a removable plug 38. Substantially directly opposite the inlet or mouth of the sand passage 21 the fitting 18 is formed with a preferably upwardly inclined extension terminating in a clean-out opening 39 which is 45 normally closed by a removable cap or cover 40 detachably secured to said fitting by cap screws 41. The cap 40 carries a grid or sieve 50 for preventing the entry of stones or other obstructions into the sand passage 21, said grid comprising a plate 42 disposed with its median plane substantially diametric of the mouth of the sand passage and having parallel fingers 43 (see also Fig. 3) projecting laterally from its opposite faces.

55 It will be understood that flow of sand through the sander to the rail is controlled by the admission of air under pressure through the pipe 30 and the air passage 27 by suitable 60 operation of the engineer's valve. When the supply of air is cut off, the sand in the supply chamber will assume approximately the position indicated in Fig. 2, the overhanging dam or baffle 22 preventing the entry of any considerable amount of sand into the sand

65 passage 21, and the length and horizontal position of the latter preventing the improper discharge of sand from the apparatus at this time. The dam or baffle 22 also controls the entry of sand into the passage 21 and permits the entry of only a limited amount into said 70 passage at any time. When the air is turned on, a jet is delivered by the nozzle 35 into the sand supply chamber to agitate the sand at the mouth of the passage 21, and a similar jet is directed through the nozzle 32 into the outlet 23, thereby causing the loosened sand to be drawn by ejector action through the relatively contracted passage 21, to be mixed with air, and to be discharged into said outlet and thence through the pipe 24 to the rail. By 75 means of the construction shown, a light and uniform flow of sand is provided, thereby causing the device to operate efficiently and without waste. The grid formed by the plate 80 42 and fingers 43 prevents the entry into the sand passage 21 of stones or lumps too large to pass therethrough, while the straight unobstructed lower wall of said passage not only permits the sand to flow freely and even- 85 ly under the action of the air but permits any obstruction which may pass the grid to move freely along with the sand and pass out at the outlet. Should, however, any obstruction become lodged in the sand passage 21 or in the sand supply chamber, it may be readily and quickly removed through the clean-out opening 25 or 39 by removing the plug 26 or cover 40, as the case may be, without disconnecting the apparatus. It is found in practice that, 90 due to the extended portion of the chamber 18 with which the cleanout opening 39 communicates, the cover 40 can be removed when the sander is in operation without substantial loss of sand through said cleanout opening, thereby permitting observation of the 95 operation and the convenient removal of any obstruction which tends to impede it. This ability to remove the cover 40 when the device is in operation without loss of sand is 100 further contributed to by the upward inclination of the extension in question, which inclination, however, is preferably not sufficient to prevent direct access to the passage 21 through the cleanout opening 39. Accord- 105 ingly, due to the substantially straight form of said passage, and the provision of the cleanout openings 25 and 39 at the opposite ends thereof, it is possible to pass a straight implement, introduced through either of said 110 openings, completely through said passage to dislodge an obstruction which might otherwise be difficult of removal and force the same through the other of said openings. The generally downward inclination of the 115 air passage 27 from its inlet 28 causes any scale or other foreign matter entering said passage to move downwardly toward the dead end thereof, thereby reducing the tendency of said foreign matter to become lodged at 120 125 130

the inlets of the air ports, this tendency being further reduced by the heads 36 which elevate said inlets above the bottom wall of said passage. A quantity of oil-saturated waste 44 is preferably placed in the lower dead end 5 of the air passage 27 adjacent the clean-out opening 29 and serves to collect any scale or sediment reaching said end and prevent its rebound into the vicinity of the air ports. 10 From time to time the plug 31 may be removed and the waste 44 renewed. At this time, by opening the engineer's valve, the compressed air may be caused to sweep through the passage 27 and opening 29 to 15 force out any sediment which may have been deposited in said passage at any point. If, however, notwithstanding the foregoing provisions, there should become lodged in the inlet of either air port an obstruction which can 20 not be blown out by the sweep of air through the air passage, such obstruction can be readily dislodged through the clean-out opening 37 by removing the plug 38.

As above pointed out, the jet of air delivered 25 by the nozzle 35 is substantially aligned with the mouth or inlet of the sand passage 21, so that said jet is delivered directly into the body of sand in the supply chamber to agitate and loosen the same and cause it to 30 be carried along by the air currents in said passage 21. It will be observed, however, that the direction of said jet is such as not to cause the same to impinge upon any of the walls of either the sand chamber or the sand 35 passage, so that while it performs its intended function in an efficient manner, there is no tendency to abrade said walls by the action of the sand blast.

The construction shown in Fig. 4 is substantially identical with that shown in Fig. 2 40 with the exception that the fitting 20 is shown as connected directly with the sand box 45 instead of with a separate fitting receiving the sand from the sand box through a supply pipe. It will be seen that in this construction the sand box 45 itself constitutes the sand supply chamber or reservoir, the operation being otherwise substantially as in the construction first described.

50 Figs. 5 to 8 illustrate a duplex installation for delivering sand at a plurality of points simultaneously, as, for example, in front of the forward driving wheel 46 and behind the rear driving wheel 47 of a locomotive. In 55 this construction the horizontally disposed fitting 180, corresponding to the fitting 18 in the construction first described, is formed with an ear 48 for attachment to the locomotive boiler, with oppositely disposed outlets 60 to which are connected substantially identical sand drafter fittings 20, and with an inlet between said outlets with which the sand supply pipe 19 communicates. In this construction the clean-out opening 390 normally closed 65 by the removable cap 40 is located substan-

tially opposite the sand supply pipe connection and substantially midway between the inlet ends of the fittings 20, and the grid 420 carried by said cap is disposed crosswise of the sand chamber adjacent the end of the sand supply pipe and substantially diametric 70 of the sand passage in the latter.

The duplex arrangement last described, in addition to simplifying the installation by the employment of a single outside sand box connection or supply pipe 19, also serves to guard against stoppage of the sand supply through either sand drafter due to disuse. In locomotives having separate pneumatic sand drafters for front and rear driving 80 wheels, as heretofore installed, separate sand supply connections for the respective sand drafters have been employed. In such an installation, when either sand drafter remains unused for any considerable time (as 85 frequently occurs in the case of the sander for the rear driver when the locomotive is in main line service), the sand in the supply connections, supply chamber, and sand passages becomes caked and, due to the heat of 90 the boiler, baked into a solid mass which, before the sander can be again used, must be broken up by a suitable implement and removed. Such caking of the sand also results in corrosion of the walls of the sand 95 passages, so that even after the removal of the obstruction the free flow of sand is interfered with. In the installation herein shown, in which sand is supplied to both drafters through a common supply pipe and chamber, 100 and in which sand enters the passages in the drafters only when the latter are in operation, it will be seen that, so long as either drafter is in service, there is no opportunity 105 for caking of the sand in any of the supply or delivery passages or chambers of either.

Having thus described our invention, we claim:

1. A track sander having a substantially straight horizontal sand passage leading laterally from the sand supply chamber or reservoir, a grid disposed adjacent the mouth of the passage, a downwardly disposed outlet leading from the outer end of said passage, and means for discharging air under 110 pressure into said passage to cause sand to flow from said chamber or reservoir to said outlet.

2. A track sander having a sand supply chamber or reservoir, a sand passage communicating therewith, and a grid in said chamber or reservoir adjacent the end of said passage, said grid including a flat member presented edgewise to said passage and disposed substantially diametric thereof.

3. A track sander having a sand passage, a sand supply chamber or reservoir, and a grid in said chamber or reservoir adjacent the end of said passage, said grid comprising a plate disposed with its median plane sub-

- 24
- stantially diametric of said passage and having parallel fingers projecting laterally from its opposite faces.
4. A track sander having a sand supply chamber or reservoir, a sand passage, a clean-out opening for said chamber or reservoir, a cover for normally closing the said clean-out opening, and a grid carried by said cover and lying adjacent the inner end of said passage when said cover is in place.
5. A track sander having a substantially straight horizontal sand passage leading laterally from the sand supply chamber or reservoir at the bottom of the latter, an inclined air passage above said sand passage, means for supplying air under pressure to said air passage, and air ports connecting said passages above the lower end of said air passage.
6. A track sander having a sand passage, an air passage above said sand passage, means for supplying air under pressure to said air passage, and air ports connecting said passages, the inlets of said ports being elevated above the adjacent bottom wall of said air passage.
7. A track sander having a sand passage, an air passage having an inlet at one end and a normally closed cleanout opening at the other, means for supplying air under pressure to said inlet, and air ports connecting said sand and air passages intermediate the ends of the latter.
8. A track sander having a sand passage, an air passage terminating at one end of the sander, means for supplying air under pressure to said air passage, an air port connecting said passages, and a normally closed cleanout opening in the exterior of the sander communicating with said air passage adjacent said air port.
9. A track sander having a sand supply chamber or reservoir, a sand passage leading therefrom, an air passage, means for supplying air under pressure to said air passage, air ports connecting said passages and arranged respectively to discharge jets of air into the outlet of said sand passage and into said chamber or reservoir adjacent the inlet of said sand passage, and a normally closed cleanout opening communicating with said air passage, the inlets of both of said air ports being adjacent said cleanout opening.
10. A track sander installation for locomotives and the like comprising a fitting providing a central sand chamber, a single sand supply pipe communicating therewith, and sand drafters communicating with said central chamber at opposite sides and each adapted to draw sand from said chamber and discharge it upon the rails, said fitting having a normally closed cleanout opening substantially opposite said supply pipe and substantially midway between the sand draf-connections.
11. A track sander including a horizontally disposed fitting providing a sand supply chamber having oppositely disposed outlets and an inlet between said outlets, and a grid disposed crosswise of said chamber opposite said inlet to restrict the flow of sand through the latter.
12. A track sander installation for locomotives and the like having a central sand chamber, a single sand supply connection 75 communicating therewith, substantially horizontal sand passages leading in opposite directions from said chamber, a dam or baffle projecting into said chamber above each of said passages, and means for discharging air 80 under pressure into either of said passages to cause sand to flow therethrough from said chamber.
13. A track sander having a sand supply chamber, a sand passage leading laterally 85 from said chamber, means for discharging air under pressure into said passage to draw sand from said chamber thereinto and discharge the same therefrom, and an extension communicating with said chamber at the side 90 thereof opposite said passage and having a normally closed cleanout opening at its outer end.
14. A track sander having a sand supply chamber, a sand passage leading laterally 95 from said chamber, means for discharging air under pressure into said passage to draw sand from said chamber thereinto and discharge the same therefrom, said chamber having an upwardly inclined portion opposite said passage, and a normally closed cleanout opening communicating with said inclined portion.
15. A track sander having a sand supply chamber, a substantially straight sand passage leading laterally from said chamber, an outlet leading from said passage adjacent the outer end thereof, a normally closed cleanout opening at the end of said passage beyond said outlet, a normally closed cleanout opening communicating with said chamber directly opposite said passage, and means 105 independent of said cleanout openings and of the closures therefor for discharging air under pressure into said passage to cause sand 110 to flow from said chamber to said outlet.
16. A track sander having a sand supply chamber, a substantially straight, horizontal, unobstructed sand passage leading laterally from said chamber and terminating 120 in a downwardly disposed outlet, the cross-sectional area of said passage being relatively small with respect to that of said outlet, and means for discharging a jet of air under pressure outwardly through said outlet, said sand passage forming a substantially straight, horizontal, unobstructed path of travel for the sand from said chamber to said outlet.
17. A track sander having a sand supply 125

chamber, a substantially straight, horizontal, unobstructed sand passage leading laterally from said chamber and terminating in a downwardly disposed outlet, the cross-sectional area of said passage being relatively small with respect to that of said outlet, means for discharging a jet of air under pressure into said chamber immediately above the inlet of said passage, and means for discharging a jet of air under pressure outwardly through said outlet.

5 In testimony whereof we affix our signatures.
